UNITED STATES PATENT OFFICE.

HENRY E. WILLER, OF MILWAUKEE, WISCONSIN.

SCREEN-FRAME, &c.

SPECIFICATION forming part of Letters Patent No. 636,879, dated November 14, 1899.

Application filed May 26, 1899. Serial No. 718,370. (No model.)

To all whom it may concern:

Be it known that I, HENRY E. WILLER, of Milwaukee, in the county of Milwaukee and State of Wisconsin, have invented a new and 5 useful Improvement in Screen - Frames or the Like, of which the following is a description, reference being had to the accompanying drawings, which are a part of this specification.

10 My invention has relation to improvements in screen-frames or the like, the invention possessing particular utility in reference to those frames known as "sliding" frames.

Heretofore difficulty has been experienced 15 in properly fitting and adjusting screen-frames to window-frames. A form of screen-frame has been provided wherein a deep groove is formed in one of the side edges thereof, in which groove are placed bowed 20 springs, which latter are adapted to bear against the bead of the window-jamb. This groove is made deeper than the width of the bead, so that the frame can be moved toward the bead when sufficient force is applied to 25 overcome the tension of the spring. The movement provided for is such that the opposite bead is permitted to disengage the more shallow groove in the opposite edge of the screen-frame, so that said frame can be 30 then swung out. This construction of course also provides for readily adjusting the frame to place. When adjusted to place, however, it has been found in practice that there are 35 in many instances gaps or spaces left between the shallow-grooved molding and the bead.

Another form of construction has been adopted wherein in the deep groove is placed a bowed spring or springs, while one of the flanges of the shallow groove is made wider 40 than the opposite flange of said shallow groove, the wider flange being of such width that while the frame can be moved edgewise, yet said flange will at all times overlap the bead and close the space between the same 45 and the screen-frame and at the same time prevent the screen-frame from being accidentally forced out of the window-frame, and in this shallow groove is arranged so-called "justifying" devices or shoes, in connection 50 with means for positively adjusting said devices so that if the window-frame is not true one of the shoes may be forced outwardly

and, if necessary, the other shoe drawn inwardly. This device, it will be understood, contemplates the placing of the bowed springs 55 in one of the grooves and justifying devices separate from the springs in the opposite groove.

The primary object of my invention is to obtain all the desirable features of the last- 60 referred-to construction in a device wherein the justifying devices and the springs are combined and placed in the deep groove of the screen-frame, the adjustability of the justifying device and the tension of the spring 65 being regulated automatically.

With the above primary object in view the invention consists of the devices and parts or their equivalents, as hereinafter more fully set forth.

In the accompanying drawings, Figure 1 is a front elevation of a screen-frame adjusted to the outside of a window-frame and showing my attachments properly applied, parts being broken away for clearness of illustration. 75 Fig. 2 is a horizontal section through Fig. 1. Fig. 3 is a detail longitudinal sectional view of one of the shoes. Fig. 4 is an end view of said shoe; and Fig. 5 is a fragment of the screen-frame, showing the pivoted button. 80

Referring to the drawings, the numeral 5 indicates a wall or side of a building provided with an ordinary form of window-frame 6, the side jambs thereof provided with the usual beads 7 7'.

The numeral 8 indicates a frame, preferably, and as shown in the accompanying illustration of the invention, a sliding screen-frame. This frame is shown as provided on one side edge with a longitudinal groove 9, 90 which the bead 7 is adapted to fit. This groove is deeper than the width of the bead, so that the screen-frame can be moved edgewise toward the bead. In its opposite side edge the screen - frame is provided with a 95 flange 10, which overlaps the bead 7'. The edge of the screen-frame where the flange 10 is located has pivoted thereto a button or buttons 18, two being preferably employed. (See Figs. 1, 2, and 5.) These buttons fit in depressions 19, formed in the screen-frame, and the pivot of each button consists of a screw 20, the head of the screw fitting in a central depression in the button. From this central

depression extends a straight recess or slot 21. When the screen-frame is in place, the buttons are turned so as to project outwardly, as shown in the drawings, whereby the bead 5 7' is confined between the flange 10 and the buttons and the screen-frame thereby held in place. The buttons are held in their adjusted position by tightening the pivot-screws. Whenever it is desired to remove the screen-frame, the pivot-screws are loosened and the buttons turned into the depressions 19, so as not to project outwardly. The turning of the buttons is readily accomplished by placing a screw-driver or other tool in the recess 15 or slot 21.

In the groove 9 are fitted two of the improved attachments. Both of these attachments are of similar form and consist of a main portion 11, to which is attached at any 20 suitable or desirable point, by means of a rivet 12 or other desirable means, an outwardly-bowed spring 13, the free end of said spring passing through a slot 14 in the base of the shoe, the spring bearing against the 25 inner edge of the outer cross-piece 15, formed by the slot 14. Each shoe is shown as provided with two side pieces 16 16, which advisably gradually increase in width in the direction of the bow of the spring. The shoes 30 are shown as disposed in the groove 9, and one end of each shoe (the end opposite to the end through which the spring protrudes) is pivoted to the inner wall of said groove by means of a screw 17 or equivalent. It will be 35 noticed that the screw is not turned inwardly to its full extent, (see Fig. 3,) whereby a slight play of the end of the shoe beneath the head of the screw is permitted in order to provide a pivot or for the outward swinging of the 40 free end of the shoe. The shoes are preferably, although not necessarily, arranged so that the lower shoe will have its end through which the spring protrudes pointing downward and the upper shoe in such position as 45 to have its end through which the spring protrudes pointing upward. When the shoes are secured as described and the screen-frame properly adjusted to the window-frame, the side flanges 16 of the shoes will receive 50 therebetween the bead 7 of the window-frame with the bowed portions of the springs bearing against the edge of said bead. The extremity of each spring will also bear against the inner wall of the groove 9, and in order 55 to prevent the sharp edge of this extremity of the spring from bearing against the inner wall of the groove said extremity is preferably reversely curved slightly, as clearly shown in Figs. 1 and 3. When the screen-frame is properly adjusted, the opposite bead 7' of the window-frame fits between the flange 10 and the buttons 18.

From the above description of the construction of my invention it will be evident that 60 when the window-frame is not true or has irregularities therein the shoes will automat-

ically compensate for such irregularities, and the screen-frame will therefore fit nicely to the window-frame notwithstanding such irregularities and will also be capable of sliding freely. It will be seen that the spring itself holds the free end of the shoe outwardly, so that the sides of said shoe will embrace the bead 7, inasmuch as the extremity of the free end of each spring is constantly contacting with the inner wall of the groove 9. The free end of the shoe is more positively held outwardly by providing for the spring bearing against the edge of the cross-piece 15. The bow of the spring acting against the bead 7 80 also creates a constant tension on the spring, which tension will necessarily automatically adjust itself to any variations in the window-frame and will also adapt the screen-frame to be held constantly out in position to which 85 it may be adjusted.

While I have herein shown and described certain details of construction, yet I do not wish to be understood as restricting myself thereto, inasmuch as modifications and variations may be made without departing from the spirit and scope of my invention. For instance, the particular and special form of shoe shown is not absolutely necessary, and any desirable form, in combination with a 95 bowed spring, which will accomplish the same function as that described in reference to these parts is deemed by me to be comprehended by my invention. It is also not absolutely necessary that the combined shoe and 100 spring need be located in a groove in the edge of the sash, as the groove may be omitted and merely an outer flange provided of sufficient width to overlap the bead of the window-frame. Furthermore, if desired, the slot 14 105 may extend entirely through the free end of the bottom of the shoe and the cross-piece 15 be thereby omitted. This cross-piece, however, is advantageously employed, inasmuch as by the engagement of the bowed spring therewith the free end of the shoe is more positively held outwardly.

While I have described my invention with particular reference to screen-frames, yet I 115 wish to be understood as claiming the same in connection with any form of frame in windows or otherwise where the attachments may be found useful.

While I have herein shown and described the buttons 18, yet it is obvious that these 120 buttons may be omitted and a groove formed in the edge of the screen-frame to receive the bead 7', one of the flanges of said groove being made wider than the other.

What I claim as my invention is—

1. A combined justifying and yielding device for screen-frames, or the like, consisting of a justifying member and a bowed spring secured to the justifying member, said spring having its free end protruding laterally beyond the base or bottom of said justifying member.

2. A combined justifying and yielding device for screen-frames, or the like, consisting of a shoe composed of a bottom piece and side pieces or flanges, and a bowed spring secured 5 to the shoe, said spring having its free end protruding laterally beyond the bottom of the shoe.
3. A combined justifying and yielding device for screen-frames, or the like, consisting 10 of a justifying member provided with a slot in its base or bottom, and a bowed spring secured to the justifying member, said spring having its free end protruding through the slot in the base of the justifying member.
- 15 4. The combination, with a screen-frame, or the like, of justifying devices pivoted to the edge of the frame, and bowed springs secured to the justifying devices, and having their free ends protruding laterally beyond the base 20 of the justifying devices and engaging the edge of the frame.
5. The combination, of a screen-frame, or the like, justifying devices pivoted at the edge of the frame, said justifying devices provided with slots, and bowed springs secured 25 to the justifying devices, and having their free ends extending through the slots and bearing against the edge of the frame.
6. The combination, of a window-frame provided with a vertical bead, a screen-frame, or the like, justifying-shoes pivoted at one edge 30 of the frame, and bowed springs secured to the justifying devices, and having their free ends extending laterally beyond the bases of the justifying devices and engaging the edge 35 of the frame.
7. The combination, of a screen-frame, or the like, justifying-shoes pivoted at the edge of the frame, and comprising a bottom or base portion and side flanges, a bowed spring secured to each justifying device, and having its free end protruding laterally beyond the base of its justifying device and bearing against the edge of the frame. 40
8. The combination, of a screen-frame, or the like, having a flanged edge, justifying devices pivotally secured at said edge, and a bowed spring secured to each justifying device and protruding laterally beyond the base of said justifying device, and bearing against 45 the edge of the frame.
9. The combination, of a screen-frame, or the like, provided with a grooved edge, pivoted justifying devices arranged in the groove, and a bowed spring secured to each justifying device, and protruding laterally beyond the base thereof, and bearing against the inner 50 wall of the groove of the frame.

In testimony whereof I affix my signature in presence of two witnesses.
